MAGNETICALLY-ACTUATED SWITCH DEVICE**Adriano Cavalieri Ducati, Milan, Italy, assignor to G. M. Giannini & Co., Inc., Pasadena, Calif.**

Application July 26, 1955, Serial No. 524,333

7 Claims. (Cl. 200—87)

This invention relates to improvements in magnetic switches, and particularly to an improved magnetic switch of the type having magnetizable contact members in a sealed non-magnetic envelope and actuated from outside the envelope by magnetizing the contacts.

One common type of magnetic switch utilizes flat, blade-type electrodes which are mounted resiliently in a cylindrical envelope in overlapping relation. A coil is wound on the envelope to provide a magnetic field source. When an electric current is passed through the coil, the blades become magnetized and are drawn together. In such a construction, there is considerable space within the envelope that is not filled with magnetic material. This results in a waste of power in the magnetizing system, as the field strength must be great enough to act through the space between the field winding and the electrodes in order to magnetize the electrodes.

An alternative construction that decreases the effective electrical force required utilizes resiliently mounted contact electrodes of circular cross section which substantially fill the space inside the envelope. In a typical case, the electrodes have beveled overlapping ends which come together when the magnetizing field is established.

The present invention is directed toward an electrode construction that retains the primary advantages of the circular cross section electrode, and that has the further advantage of being particularly adapted for very high frequency switching. It has the additional advantage of being less sensitive to accelerating and decelerating forces such as are exerted when the switch is used in equipment traveling at high speeds, as in aircraft and the like. In certain instances, the improved switch construction of the present invention further lends itself readily to provision of a single-pole, double-throw switch.

In a preferred embodiment of the invention, a pair of rigidly mounted electrode elements cooperate with a third movable electrode which, when magnetized, moves to bridge a gap between the fixed electrodes. Since the movable electrode is small compared with the two fixed electrodes, it is feasible to fill substantially all of the envelope space with magnetizable material to minimize the required magnetizing force, while keeping the movable element small enough to have it respond readily to high frequency switching operation. In some instances, the movable electrode may be arranged for bi-directional movement so as to reduce the likelihood that vibration or other accelerating or decelerating forces will affect operation of the switch.

A more complete understanding of the invention, and of further objects and features thereof, can be had from the following description of illustrative embodiments thereof, when considered in connection with the accompanying drawings, wherein:

Figure 1 is a sectional plan view of a switch embodying the invention;

Figure 2 is a sectional end view of the switch of Figure 1, taken on the line 2—2 of Figure 1;

2

Figures 3 and 4 show switches having modified electrode arrangements embodying the invention;

Figure 5 is a perspective view of a portion of the switch shown in Figure 4;

5 Figure 6 shows another relay switch that is statically and dynamically balanced;

Figure 7 is a perspective view of the movable element of the switch shown in Figure 6; and

Figure 8 shows another dynamically balanced relay switch.

Figure 1 of the drawing shows a magnetic switch embodying the invention and comprising a pair of elongated magnetizable electrodes 10 and 12. These electrodes are of circular cross section and are formed of soft iron or other readily magnetizable material and serve both as magnetic field conductors and as contact members through which electric current will flow.

The electrodes 10 and 12 are supported in fixed positions in opposite ends of a cylindrical glass envelope 14 by relatively short, stiff, Kovar metal leads 16 and 18. These leads are secured by soldering, welding or the like to the opposite ends of the electrodes 10 and 12 and extend through seals in the envelope end walls. This provides electrical access to the electrodes from outside the envelope and also supports the electrodes rigidly in end-to-end relation in axial alignment with each other, with a gap between their adjacent ends. In this, and the other relay switches shown herein, the envelope 14 may be of glass or any non-magnetic material such as aluminum, copper, etc.

In the space between the two fixed electrodes, there is provided a third movable electrode 20. This electrode 20, which is also made of magnetizable material, comprises flattened, ring-like end portions 22 formed integral with a connecting spiral spring portion 24 which tapers inwardly from the end portions toward the center. The reduced diameter central part of the spring fits loosely about a guide pin 26 in this instance of insulating material (although it may be conductive) which is set into the end of the fixed electrode 10 and extends axially from this electrode slightly more than half of the distance toward the other fixed electrode 12. The spring 24 is made of magnetic material, e.g. soft iron. The deflection of this spring is slight and within the limit of elasticity of the soft iron wire.

The relaxed height of the connecting spring portion 24 is made sufficiently less than the length of the gap separating the fixed electrodes so that the movable electrode 20 will always be out of contact with at least one of the fixed electrodes when the switch is not magnetized. Of course, the unmagnetized movable electrode 20 may be spaced from both fixed electrodes 10 and 12. Thus, when the switch is not magnetized, there will always be an open-circuit between the lead wires 16 and 18.

55 A magnetizing winding 28 surrounds the envelope 14 to establish a magnetic field through the envelope when electric current is passed through the winding. Obviously, a permanent magnet or any other means can be provided to supply the necessary magnetic flux. The spring portion 24 of the movable electrode 20 is made 60 sufficiently resilient to be overcome readily by the magnetic attracting force between the movable electrode end sections 22 and the fixed electrodes 10 and 12 when the switch is magnetized. When the end portions 22 make contact with the ends of the electrodes 10 and 12, the circuit is completed through the switch through the lead wire 16, the fixed electrode 10, the movable electrode 20, the fixed electrode 12, and the support lead 18.

It can be seen that the very small mass of the movable electrode 20, with its small inertia, makes it possible to operate the switch at very high switching frequencies. Also, the arrangement is such that "G" forces and accel-

eration and deceleration forces will have minimum effect on the switch.

It is evident that the movable electrode 20 can be made integrally of a single piece of magnetizable material, such as iron wire, or can be made of two separate discs or rings of similar material fixed to the ends of a spring.

In order to insure making good contact, the contact surfaces at the facing ends of the electrodes 10 and 12 can be coated with suitably conductive contact material, such as silver, tungsten, platinum or the like. Similarly, the contact faces of the end portions 22 preferably will be coated with such contact material. To reduce further the possibility of corrosion of the electrodes as well as arcing at the contacts, the envelope 14 may be evacuated or may be filled with inert gas such as helium or the like.

To facilitate assembly of the parts in proper alignment, as well as to help maintain the fixed electrodes 10 and 12 in proper position, resilient locator rings 29 may be provided which are positioned in grooves 31 in the electrodes 10 and 12 and press against the inner surface of the envelope 14 at spaced points, as shown best in Figure 2.

Figure 3 shows another electrode structure in which the adjacent end portions of the fixed electrodes 10 and 12 are each provided with a recess or notch formed by removing a semi-circular segment from the circular electrode. The notches thus formed are located on opposite sides of the fixed electrode axis so that the semi-circular end portion 10a, 12a of each electrode is in longitudinal alignment with the recess of the other electrode. Thus, there is a substantial gap between the semi-circular end portion of each fixed electrode and the main body portion of the other fixed electrode. Also, these end portions 10a and 12a are spaced from each other both laterally and longitudinally.

The movable electrode in this switch comprises a thin, flat, magnetizable disc 32 provided with a central hole 34 to fit loosely on an axial resilient guide wire 36 which extends between insulating mounting jewels 38 set into the fixed electrodes. The disc 32 is held loosely in the gap between the ends of the fixed electrodes by the guide wire, and although it may be constructed to slide back and forth on the wire and contact one or the other fixed electrode, it cannot normally make contact with both of them simultaneously. This is insured by making the central hole 34 small enough to prevent the disc 32 from tilting sufficiently to bridge the gap between the electrode end portions 10a and 12a unless enough moment is applied to overcome the resilient force of the wire 36.

When the switch is magnetized, the disc 32 will be attracted simultaneously toward the fixed electrode end portion 10a on one side, and toward the other fixed electrode end portion 12a on the other side. This will tilt the disc and apply a bending force to the guide wire 36 at the center, permitting the disc to tilt sufficiently to make contact with both fixed electrodes 10 and 12. It will be understood that the recesses cut into the ends of the fixed electrodes serve to channel the magnetizing field so that it will act in opposite directions on opposite halves of the disc to achieve the desired effect.

The contact disc is free to rotate on the wire 34 so that under ordinary conditions of use the entire rim of the disc 32 serves from time to time as the area of contact. The freely rotatably disc 32 presents continually changing contact surfaces for uniformity of wear. As before, it is preferable to coat all of the contact surfaces with suitably conductive material.

Alternatively, the disc 32 can be firmly secured to the wire 36, as by soldering or the like, and the wire permitted to rotate in the mounting jewels 38 to provide a continually changing contact area.

As with the switch shown in Figure 1, the embodiment

illustrated in Figure 3 has a movable electrode of very small mass for high frequency switching and also a design that minimizes actuation of the switch by "G" forces and acceleration and deceleration forces.

In Figure 4, there is shown a double-throw switch. As before, the adjacent end portions of the fixed electrodes are notched to form spaced offset ends 10a and 12a. The movable electrode in this case comprises a magnetizable disc 40 which is held resiliently against the end of one fixed electrode 12, by a spring 42 which is secured to the electrode 12 and to the disc 40 by welding, soldering or the like. The disc 40 also normally engages a supplementary fixed contact 44 which comprises a copper or other non-magnetic wire. This contact wire 44 extends through an end seal in the envelope 14 and through an insulating sleeve 46 disposed in a longitudinal channel 48 (see also Figure 5) in the electrode 12, being held in place at spaced points 50 by peening the channel walls over the sleeve 46, or other suitable means.

Thus, when the movable electrode member 40 is in the position shown in Figures 4 and 5 (the switch unmagnetized), a first circuit will be completed through the contact wire 44, the disc 40, the fixed electrode 12, and the support lead 18. Accordingly, the disc 40 and the contact wire 44 constitute a first set of contacts (normally closed) in the switching device.

The fixed electrode 10 and the movable electrode 40 constitute a second set of contacts (normally open) in the switching device of Figure 4. These contacts 10 and 40 will be brought into engagement with each other when current is passed through the magnetizing winding 28 as the magnetic field will cause the movable electrode 40 to be attracted toward the projecting end portion 10a of the electrode 10, and the projecting end portion 12a of the electrode 12. This, of course, will break the circuit through the supplementary contact 44 and the movable contact 40, and establish a new circuit which will include the lead wire 16, the fixed electrode 10, the spring 42, the movable electrode 40, the fixed electrode 12, and the lead wire 18.

As in the other embodiments of the invention previously described, it can be seen that the relatively small movable electrode in the switching device of Figure 4 is well adapted for high frequency switching operations, and is statically and dynamically balanced.

Figures 6 and 7 show another balanced relay switch in which the movable contact member 54 (shown separately in Figure 7) has a cylindrical central portion 56 and oppositely-extending offset contact portions 58 and 60 of semi-circular cross-section. This movable contact 54, which is formed of magnetic material, is mounted in the envelope 14 by a rubber ring 62, which may be similar to an O-ring, positioned in a peripheral groove in the outer surface of the central portion 56. The ring 62 is retained also in a corresponding groove in the inner surface of the envelope 14.

The members 10 and 12 are formed of iron or other magnetic material and preferably are circular in cross section. These members 10 and 12 are provided with contact portions 10a and 12a, respectively, which extend in juxtaposition with the two contact portions 58 and 60 of the movable member 54. The areas of contact between the member 54 and the fixed electrodes 10 and 12 are coated with suitable contact metal as indicated at 64 and 66.

In operation, when a magnetic field is produced, as by energizing the winding 28, the member 54 is caused to tilt so that it makes contact with the members 10 and 12 to complete the electric circuit between the leads 16 and 18.

When the magnetic field is removed the contacts are opened by the restoring force of the resilient rubber ring 62.

Alternatively, the movable contact member can be mounted on a transverse pivotal wire. One such arrangement is shown in Figure 8 in which the fixed electrodes

10 and 12 may be identical with those of Figure 6. In this illustration the movable contact member 70 is in the form of a strip of magnetic material such as iron. This member 70 is secured to and supported by a torsion spring wire 72 which extends transversely through the member 70 and is secured to the walls of the envelope 14. The wire can be sealed into opposite sides of the wall of the envelope 14 or an internal structure can be provided to support it.

When the magnetic field is produced, the member 70 rotates about the wire 72 as an axis and completes the circuit between the fixed electrodes 10 and 12. When the magnetic field is removed, the spring torsion force of the pivot wire 72 returns the member 70 to its normal open-circuit position.

To simplify the description, similar parts of the various views have in some instances been assigned corresponding numbers. Certain parts of the construction of each illustration have not been described in detail, and in these instances the construction can be the same as that described in connection with the other views or in accordance with structures already known in the art.

What is claimed is:

1. A magnetically-actuated switch device having a quick response and which is relatively unaffected by gravitational and acceleration and deceleration forces comprising a relatively long, generally cylindrical sealed envelope, first and second generally cylindrical members of magnetizable material fixed in position one in each end of said envelope, said members being in axial alignment with each other, the adjacent ends of said members having first and second laterally offset end portions, respectively, which are offset to opposite sides of the longitudinal axes of said members, the outer surfaces of said end portions being generally cylindrical, a small light weight movable electrode between said first and second end portions and having first and second sides which are shaped to conform to the outer surfaces of said first and second end portions, respectively, resilient mounting means secured to said small electrode between said sides and swingably mounting said electrode for swinging movement about a pivot axis mid-way between said sides and passing between said first and second end portions and generally perpendicular to the axes of said members, said resilient mounting means normally urging the first and second sides of said small electrode in opposite directions away from said first and second end portions, and magnetic control means outside of said envelope for changing the magnetic condition of said members and their laterally offset end portions, thereby to urge the first and second sides of said small electrode in the respective reverse directions toward said first and second end portions, respectively.

2. A magnetically-actuated switch device having a quick response and which is relatively unaffected by gravitational and acceleration and deceleration forces comprising a relatively long, generally cylindrical sealed envelope, first and second generally cylindrical members of magnetizable material fixed in position one in each end of said envelope, said members being in axial alignment with each other and with the longitudinal axis of the envelope, the adjacent ends of said members having first and second laterally offset pole portions, respectively, which are offset to opposite sides of the longitudinal axes of said members, the outer surfaces of said pole portions being generally cylindrical, a small light-weight movable electrode between said first and second pole portions and having first and second edges which are shaped to conform to the outer longitudinal surfaces of said first and second pole portions, respectively, the inner surface of said envelope being closely adjacent to the edges of said small electrode and the outer longitudinal surfaces of said pole portions, resilient mounting means secured to said small electrode between its edges and swingably mounting said small electrode for swinging movement about a pivot

axis mid-way between its edges and passing between said first and second pole portions and generally perpendicular to the axis of the envelope, said resilient mounting means normally urging the first and second edges of said small electrode in opposite directions away from said first and second pole portions, and control winding means

5 outside of said envelope and closely around said small electrode for changing the magnetic condition of said members and their laterally offset pole portions, thereby to swing the first and second edges of said small electrode about the pivot axis in the respective reverse directions toward said first and second pole portions, respectively.

3. A magnetically-actuated switch device having a quick response and which is relatively unaffected by

15 gravitational and acceleration and deceleration forces comprising a relatively long, generally cylindrical sealed envelope, first and second members of magnetizable material fixed in position in said envelope, the adjacent ends of said members being laterally displaced, a small movable element between the adjacent ends of said members, resilient mounting means secured to said small movable element and swingably mounting said small element for swinging movement about a pivot axis mid-way between its ends and generally perpendicular to the axis of the envelope, said resilient mounting means normally urging the opposite ends of said small element in opposite directions away from the respective adjacent ends of said members and magnetic control means outside of said envelope for changing the magnetic condition of said

20 members thereby to swing the opposite ends of said small element about the pivot axis in the respective reverse directions toward the respective adjacent ends of said first and second members.

4. For use in a magnetically operated switch wherein

25 a magnetic field is utilized to control electrical circuits, a switch element comprising a sealed envelope of non-magnetic material, first and second spaced magnetizable contact members in relatively fixed positions in said envelope and formed at least in part of magnetizable material,

30 each of said fixed members having an extending end contact portion of smaller cross sectional area than the body of said fixed members, said contact portions being spaced longitudinally and offset laterally, a movable magnetizable contact member formed at least in part of

35 magnetizable material and having first and second end portions, and means secured to and in electrical circuit with the contact portion of the first fixed member for supporting said movable member between said contact portions, with its first and second end portions adjacent

40 to the respective contact portions of said first and second fixed members, said first end portion being movable in a first direction toward the adjacent contact portion of the first fixed member, said second end portion being mov-

45 able in a second direction opposite to said first direction for engaging the adjacent contact portion of the second fixed member, a third fixed contact member having a

50 third contact portion spaced from the contact portions of the first and second fixed members, said supporting means resiliently biasing the second end portion of said

55 movable member out of engagement with the contact portion of the second fixed member and into engagement with said third contact portion, said first end portion of the movable member being urged in said first direction toward said contact portion of the first fixed member in

60 the presence of a magnetic field and said second end portion of the movable member being urged in the opposite direction out of engagement with said third contact portion and into engagement with the contact portion of the second fixed member in the presence of a magnetic field.

70 5. A magnetic switch element comprising a generally cylindrical sealed envelope, two generally cylindrical electrodes of magnetizable material fixed in position inside said envelope in spaced end-to-end relationship and having their longitudinal axes substantially in alignment with

each other and with the axis of said envelope, the adjacent ends of said fixed electrodes being formed into laterally offset pole portions which are laterally offset on opposite sides of the axis of said envelope, a third magnetizable electrode of disk-like shape and of relatively small mass mounted movably between said two electrodes and having two opposite edge portions, said movable circular electrode extending generally transversely of said envelope approximately perpendicular to the axis of said envelope, and resilient mounting means for mounting said movable circular electrode for swinging movement about a pivot axis passing mid-way between its opposite edge portions and between the pole portions of said fixed electrodes, said resilient mounting means urging said edge portions away from said pole portions, said opposite edge portions of said third electrode swinging about the pivot axis in opposite directions upon magnetization of said electrodes to make contact with both of said two pole portions, the cylindrical surfaces of said two electrodes and the edge portions of said third electrode being closely adjacent to the inner surface of said envelope.

6. A magnetic switch device comprising a sealed envelope, first and second electrodes of magnetizable material fixed in position in said envelope, said electrodes being spaced apart and having longitudinal axes substantially in alignment with each other, a supplementary contact element fixed in position within said envelope and insulated from said electrodes, a third magnetizable electrode movably mounted within said envelope and having two spaced areas held resiliently in respective positions in contact with said supplementary contact element and one of said two electrodes, said two spaced areas

of said third electrode being movable in opposite directions to respective second positions out of contact with said supplementary element and contacting both of said two electrodes, and means outside said envelope for magnetizing said electrodes.

- 5 7. A magnetic switch device comprising a relatively long, generally cylindrical sealed envelope, first and second generally cylindrical electrodes of magnetizable material fixed in position one in each end of said envelope, 10 said electrodes being in axial alignment with each other and with the axis of said envelope, the adjacent ends of said electrodes having offset end portions spaced longitudinally from each other, a disc-shaped, magnetizable electrode positioned between said two electrodes, resilient 15 mounting means fixed to said first electrode and said disc-shaped electrode and holding said disc-shaped electrode in a first position out of contact with said second electrode, and magnetic control means outside said envelope for magnetizing said electrodes, thereby to attract 20 said disc-shaped electrode to a second position engaging said second electrode end portion.
